UNITED STATES PATENT OFFICE

2,505,097

AMMUNITION BOX HOLDER

George H. Collins, Lynn, Mass., assignor to United
Shoe Machinery Corporation, Flemington, N. J.,
a corporation of New Jersey

Application July 1, 1946, Serial No. 680,578

2 Claims. (Cl. 248—311)

1

This invention relates to ammunition box holders and is herein illustrated as embodied in a holder adapted to support ammunition boxes for automatic guns, more particularly the caliber .30 or caliber .50 Browning machine gun.

It is an object of the invention to provide an ammunition box holder so constructed as to permit easy and rapid attachment of an ammunition box thereto and its removal therefrom.

Another object of the invention is to provide an ammunition box holder adapted to accommodate ammunition boxes of different heights and types.

A further object of the invention is to provide an ammunition box holder adapted to lock the ammunition box securely on the gun to prevent its falling off during the operation of the gun.

These and other objects and features of the invention will become apparent from the following description with reference to the accompanying drawings, in which:

Fig. 1 is a view in front elevation of one form of ammunition box holder embodying the invention;

Fig. 2 is a horizontal sectional view on the line II—II of Fig. 1;

Fig. 3 is a vertical sectional view on the line III—III of Fig. 1, indicating a metal ammunition box secured to the holder;

Fig. 4 is a view in front elevation of a modified form of ammunition box holder;

Fig. 5 is a vertical sectional view on the line V—V of Fig. 4, indicating the metal ammunition box secured to the holder shown in Fig. 4;

Fig. 6 is a view substantially similar to Fig. 5, but indicating an ammunition box of a different type secured to the same holder; and

Fig. 7 is a horizontal sectional view along the line VII—VII of Fig. 4.

In one embodiment of the invention, illustrated in Figs. 1, 2 and 3, the ammunition box holder is adapted to support a sheet metal ammunition box B, indicated by broken lines in Fig. 3, from which ammunition is to be supplied to the feed channel of a gun G, such as a caliber .30 or caliber .50 Browning machine gun, mounted on a gun support comprising a cradle C.

A mounting bracket 10 is rigidly secured, as by welding, to the gun supporting cradle C adjacent to the ammunition feed channel in the breech end of the gun. The bracket has a pair of forwardly and inwardly projecting vertical ribs 12 forming ways within which is mounted a plate 14. The lower end of the plate 14 terminates in a U-shaped flange 16 adapted to engage a flange 17 at the lower end of the wall of the ammunition

2

box facing the gun, as shown in Fig. 3. The plate 14 is provided with a pair of rearwardly projecting ears 18 which engage the lower end of the bracket 10 to prevent upward movement of the plate relative to the bracket.

The plate 14 is further provided with a pair of inwardly turned vertical ribs 20 forming ways in which is mounted a latch member 22 provided at its upper end with a hooked portion 24, which is arranged to engage a hinge 26 on the wall of the ammunition box facing the gun and to co-operate with the U-shaped flange 16 of the plate 14 to lock the box in operative position. The latch member 22 is movable heightwise relatively to the plate 14 against the tension of springs 28 anchored at their lower ends to lugs 30 extending forward from the plate 14 and, at their upper ends, to a lug 32 projecting forward from the latch member through a rectangular opening 34 in the latch member. Downward movement of the latch member 22 relative to the plate 14 is limited by its engagement with a tongue 36 projecting forward from the bracket 10 through an opening 38 in the plate 14.

To attach an ammunition box B to the holder just described, the hinge 26 on the box is placed under the hooked portion 24 of the latch member 22 and the box is pushed upward until its flange 17 engages the U-shaped flange 16 at the lower end of the plate 14. As the box is being pushed upward the latch member 22 is moved upward relatively to the plate 14 against the tension of the springs 28, which are of such strength that the box will be rigidly clamped in operative position when the flange 17 of the box and the flange 16 of the plate 14 are interlocked.

By reason of the spring connection between the latch member 22 and the plate 14, the latch member is self-adjusting to accommodate ammunition boxes of various heights.

To remove the ammunition box B from the holder, the box is pushed up until its flange 17 is disengaged from the flange 16 of the plate 14, whereupon the box is tilted to free its hinge from the hooked portion 24 of the latch member 22. Upon removal of the box the latch member 22 is returned to its initial position by the springs 28.

Figs. 4 to 7 illustrate a modified form of ammunition box holder adapted to support either metal or wooden boxes for caliber .30 or caliber .50 ammunition.

This holder comprises a plate 40 having a pair of rearwardly extending vertical ribs 41, which fit in guideways formed in a mounting bracket

42 secured to the gun cradle C adjacent to the feed channel in the breech end of the gun. The bracket 42 is provided with forwardly and inwardly extending vertical ribs 43. The lower end of the plate 40 terminates in a U-shaped flange 44 which is arranged to be engaged by the flange 17 on the lower end of the rear wall of the metal ammunition box B, i. e., the wall facing the gun, as illustrated in Fig. 5. In the spaces between the ribs 41 and the walls of the guideways in the mounting bracket 42 are inserted metal strips 45, the upper ends of which are bent outward over the upper ends of the mounting bracket and the lower ends of which are bent inward over the lower ends of the ribs 41 to lock the plate 40 against downward movement relative to the mounting bracket.

Also mounted in the bracket 42 is a latch slide 46 which is movable heightwise relatively to the plate 40 during attachment and removal of a metal ammunition box. Downward movement of the latch slide 46 relative to the plate 40 is limited by engagement of the slide with a forwardly projecting tongue 48 on the plate 40. The tongue 48 abuts against a projection 50 on the lower end of the mounting bracket 42 and prevents upward movement of the plate 40 relative to the bracket.

The latch slide 46 has lugs 52 extending rearward through an opening in the plate 40. The lugs 52 provide bearings for a rockshaft 54 extending lengthwise of the gun. Rigidly mounted on the shaft 54 is a latch member 56 having at its upper end two hooked portions 58 arranged to engage the hinge 26 on the box B, as shown in Fig. 5, and to cooperate with the flange 44 of the plate 40 to lock the box in its operative position. The hooked portions 58 of the latch member extend forward through openings 60 in the slide 46 and through an opening 62 in the bracket 42. The latch member 56 is yieldingly connected to the plate 40 by springs 64 secured at their lower ends to lugs 66 extending rearward from the lower end portion of the plate 40 and, at their upper ends, to a cotter pin 68 anchored to the latch member 56.

To attach the metal box B to the holder just described, the box is presented with its hinge 26 under the hooked portions 58 of the latch member 56 and pushed upward. As the box is pushed upward, the latch member 56 and the slide 46 are moved upward, against the tension of the springs 64, until the flange 17 at the lower end of the box engages the U-shaped flange 44 at the lower end of the plate 40, whereupon the box is clamped in operative position, as shown in Fig. 5. The box is removed from the holder in the manner described previously in connection with the holder illustrated in Figs. 1 to 3.

The manner of attaching a wooden ammunition box, such as the box B' illustrated in Fig. 6, is somewhat different from that previously described in connection with the metal box. The wooden ammunition box has no flange such as the flange 17 of the metal box but, instead, is provided with vertical grooves 70 (Fig. 6) in its side walls, and the lower portion of the rear wall facing the gun is cut at an angle and recessed

to provide a ledge 72. To attach the wooden box to the holder, the ribs 43 of the mounting bracket are caused to engage in the grooves 70 of the box and the box is moved downward until the ledge 72 seats against the projection 50 on the bracket. During the downward movement of the box, the engagement of its rear wall with the hooked portions 58 of the latch member 56 causes the latch member to swing inward. The above procedure is reversed to remove the box and, as the box is freed from the holder, the latch member 56 swings back to its initial position.

Having thus described my invention, what I claim as new and desire to secure by Letters Patent of the United States is:

1. An ammunition box holder comprising a bracket, a plate mounted in said bracket and having a box-engaging portion adapted to engage the lower end of a box of one type, yielding latching means mounted for heightwise movement relative to said plate and also for swinging movement about a horizontal axis, said latching means having box-engaging portions adapted to engage the upper end of said box and to cooperate with the box-engaging portion of said plate to clamp the box in operative position, means on said bracket adapted to support a box of a different type, and spring means connecting said plate and said latching means and against the tension of which said latching means effects its heightwise and swinging movements, whereby the latching means is rendered self-adjusting to accommodate boxes of different heights and types.

2. An ammunition box holder comprising a bracket, a plate mounted in said bracket and having a box-engaging portion adapted to engage the lower end of a box of one type, yielding and self-adjusting latching means having box-engaging portions adapted to engage the upper end of said box, ribs on said bracket adapted to engage grooves in a box of a different type, and a projection on said bracket adapted to engage a ledge on said last named box to support the box in operative position, said latching means comprising a slide movable heightwise relatively to said plate, a shaft carried by said slide, a latch member rigidly mounted on said shaft, and spring means connecting said latch member to said slide, whereby said latch member is adapted to move with said slide variable amounts heightwise relatively to said plate and to swing relatively to said slide against the tension of said spring means, to accommodate ammunition boxes of different heights and types.

GEORGE H. COLLINS.
